CLAIM

The ornamental design for a children's wagon, as shown and described.

DESCRIPTION

FIG. 1 is a perspective view of the children's wagon with seats in a raised configuration;

FIG. 2 is a front elevational view of the children's wagon with the seats in the raised configuration;

FIG. 3 is a rear elevational view of the children's wagon with the seats in the raised configuration;

FIG. 4 is a side elevational view of the children's wagon with the seats in the raised configuration, the opposite side of which is an identical mirror image;

FIG. 5 is a top plan view of the children's wagon with the seats in the raised configuration;

FIG. 6 is a bottom plan view of the children's wagon;

FIG. 7 is a perspective view of the children's wagon with seats in a folded configuration;

FIG. 8 is a front elevational view of the children's wagon with the seats in the folded configuration;

FIG. 9 is a rear elevational view of the children's wagon with the seats in the folded configuration;

FIG. 10 is a side elevational view of the children's wagon with the seats in the folded configuration, the opposite side of which is an identical mirror image;

FIG. 11 is a top plan view of the children's wagon with the seats in the folded configuration; and,

FIG. 12 is a bottom plan view of the children's wagon.
